UNITED STATES PATENT OFFICE.

JOSEPH JOHNSON, OF NEW YORK, N. Y.

MOVING-PICTURE THEATER.

1,200,845.

Specification of Letters Patent. Patented Oct. 10, 1916.

Application filed March 27, 1915. Serial No. 17,313.

To all whom it may concern:

Be it known that I, JOSEPH JOHNSON, a citizen of the United States, and residing at New York, in the county of New York and State of New York, have invented certain new and useful Improvements in Moving-Picture Theaters, of which the following is a specification, such as will enable those skilled in the art to which it appertains to make and use the same.

This invention relates to moving picture theaters, and the object thereof is to provide a theater of this class, or to improve the stage construction of theaters of this class in such manner that exhibitions of moving pictures may be given in the daytime, and in outdoor theaters or amusement places, if desired; and with this and other objects in view the invention consists in the theater construction hereinafter described and claimed.

The invention is fully disclosed in the following specification, of which the accompanying drawing forms a part, in which the 25 separate parts of my improvement are designated by suitable reference characters in each of the views, and in which:

Figure 1 is a central, vertical, longitudinal section through the stage portion of a 30 theater involving my invention and showing a dark room back of the stage; Fig. 2 a horizontal section on the line 2—2 of Fig. 1; and, Fig. 3 a front view showing parts of the construction broken away.

In the drawing forming part of this specification, I have shown at *a* the stage portion of a moving picture theater having a back wall or partition *b* in which is an approximately central opening *b*² which 35 corresponds in form and dimensions with the screen *c* to be used and across which the screen *c* is drawn or placed.

Back of the stage wall or partition *b* is a dark room *d* in the rear portion of which 45 is placed the usual picture projecting apparatus *e* by means of which pictures may be projected onto the screen *c* in the usual manner.

Over the stage *a*, or in the top of the stage 50 space are transverse vertically adjustable wings, flies or screens *f* which are suitably spaced and any number of which may be employed, and which are colored dark or black, and the stage is also provided at the 55 opposite sides thereof with other wings, flies or screens *g* which are also colored dark

or black and any number of which may be employed, and at the bottom of the front of the stage is placed a roller *h* on which is wound a colored or black screen *h*² which 60 may be drawn upwardly and forwardly into any desired position and secured in such position by any preferred means.

The vertically adjustable top screens *f* which extend across the upper part of the 65 front of the stage at right angles to the side wings *g*, are adapted to move vertically in suitable guides (not shown). These top wings or flies *f* are suspended by means of cords or cables *k*, the ends of which are 70 secured to said flies. From the point of attachment to the flies *f*, the cords *k* pass over pulleys *l* mounted on the top of the stage, and have their opposite ends secured to a rotatable drum *m* mounted on one side of 75 the stage. When the drum *m* is rotated the cords *k* will wind or unwind upon the drum and will raise or lower the top wings *f*, thus enlarging or contracting the stage opening in front of the screen *e*.

It will be understood, of course, that the audience chamber or space, not shown, is in front of the stage, and the top wings or flies *f* are placed so as to produce the top line of vision *i*, as indicated in Fig. 1, and 85 the bottom screen *h*² may be so adjusted as to produce the bottom line of vision *i*², as shown in said figure, while the side wings or flies *g* may also be placed so as to produce the side lines of vision *i*³ as shown in Fig. 2, 90 and it will be understood that the top and bottom lines of vision *i* and *i*², and the side lines of vision *i*³ may be regulated according to the size or dimensions of the audience space or chamber in front of the stage and 95 the location of the audience. It will be understood that when the said lines of vision are fixed or determined so as to correspond with a particular audience chamber or space, they need not be adjusted or adjustable, but 100 it will also be understood that when necessary or desirable the top screens or flies may be adjusted in the manner described. With this construction the pictures are thrown on the back of the screen and are clearly seen 105 by the audience in the same manner as in other theaters of this class. If the auditorium is dark, or the performance is at night the operation will be the same as of any other theaters of this class, but with 110 my improvement moving picture shows may be given in the daytime and without arti-

ficial light and even in outdoor spaces, or where the audience or audience space is not inclosed, this result being made possible by the dark room behind the rear wall or partition of the stage in which the picture projecting apparatus is placed and the wings or flies *f* and *g*. The sheet screen *h*² is not absolutely necessary but is preferably used in order to adapt the apparatus to all possible conditions, and while I have described the wings or flies *f* and *g* as colored dark or black, this also is not necessary unless the picture exhibition or show is to be given out of doors, or in an inclosed auditorium.

15 My improvement will also be an advantage when used at night, in connection with an outdoor theater, by reason of the fact that the top and side wings or flies *f* and *g* will prevent any person or persons, except those 20 sitting in the auditorium and who have paid their admission from seeing the pictures, and the details of construction necessary to carry my improvement into effect and not herein shown and described will be readily 25 understood by all those familiar with theatrical apparatus or exhibition apparatus of this class.

Having fully described my invention, what I claim as new and desire to secure by 30 Letters Patent, is:—

1. In a moving picture theater, a stage space having a partition, rearwardly of which is a dark room the partition having a screen opening across which is placed a 35 screen, the stage space being provided in front of and at a distance from said partition with a transverse top wing and with side wings or flies, and at the bottom front portion thereof with an outwardly and upwardly movable screen or fly.

2. In a moving picture theater, a stage space having a partition, rearwardly of which is a dark room, the partition having

a screen opening, across which is placed a screen, the stage space being provided at a 45 distance from said partition and at the bottom front portion thereof with an outwardly and upwardly movable screen or fly.

3. In a moving picture theater, a stage space having a partition, rearwardly of which is a dark room the partition having a screen opening, across which is placed a screen, the stage space being provided in front of and at a distance from said partition with a vertically adjustable transverse 55 top wing, and with side wings or flies.

4. In a moving picture theater, a chamber having an elongated body provided with an open end, a partition dividing the inferior of the chamber into two compartments, one 60 of said compartments being light proof and adapted to contain a picture projecting apparatus, said partition being provided with an opening across which the picture screen is placed for receiving pictures from the 65 projecting apparatus, inwardly extending vertically disposed side flaps provided in the other compartment of said chamber near the open end of the same and spaced away from said partition, and a vertically disposed flap 70 extending transversely across the upper portion of said compartment near its open end also spaced away from said partition and adapted to exclude exterior light from the screen, the lower end of said transverse flap being below the upper end of the 75 screen.

In testimony that I claim the foregoing as my invention I have signed my name in presence of the subscribing witnesses this 80 25th day of March, 1915.

JOSEPH JOHNSON
